CARRIER ROD DRIVING MECHANISM

Arnold Friedrich Verbeek, Oberlungwitz, Germany, assignor to Kaliot, Inc., New York, N. Y., a corporation of New York

Application July 6, 1936, Serial No. 89,014

9 Claims. (Cl. 66—127)

This invention relates to a new and useful improvement in flat knitting machines and specifically to the mechanisms for controlling the movements of the carrier rods.

5 While the invention may be utilized for other purposes it is of particular advantage in the knitting of "ringless" fabric of the type disclosed in Patent No. 2,018,059 granted to Albert Friedmann under date of October 22, 1935, and for that reason the form shown in the drawings and described 10 in the specification is that suitable for knitting this type of ringless fabric.

As is well known, the rings or stripes which frequently mar the appearance of sheer silk hosiery 15 are caused primarily by lack of uniformity in the thread which, in spite of the greatest care in manufacture, varies in diameter in different parts and also because it has been the practice to knit such hosiery from a single thread. This brings 20 such inequalities into adjacent courses, thereby accentuating them and producing the objectionable variations in thickness of the fabric commonly known as rings. The difficulty has been largely overcome by employing instead of one 25 thread say three separate threads utilized in rotation in successive courses so that the same thread appears only in every third course.

While this method of knitting has substantially 30 eliminated the objectionable rings it has introduced a serious defect at the extreme edge of the fabric. In fact, it is impossible to obtain a good edge for the reason that between the end of one course knit with a thread and the beginning of the next course knit with the same thread there 35 is a loose or floating length of the thread lying across the ends of the two intervening courses. Since this is true of each of the threads, the fabric over its entire length is bordered by three such floating threads. These are sometimes caught 40 by chance into the intervening courses, but usually hang loosely along the edges of the fabric where they may easily be cut or become entangled with the needles causing breakage and damaging the fabric. They also make neat seaming extremely difficult.

By the invention of this application although 45 three carriers are used to lay three separate threads in successive courses a ringless fabric is produced in which there are no floating threads. To the contrary, each of the three threads is knit 50 into each course, one forming the main full width course and the other two being knit into the respective selvages of the same course.

The invention, in addition to providing simple 55 and efficient means for imparting to the carrier

rods the motion required for laying the threads in this manner, also insures that the carrier rods involved are positively positioned against their limiting stops at the end of each stroke and that they are not dragged out of position through interference between the different carriers. This is accomplished without utilizing the latches which have been considered necessary to hold the carrier rods against their end stops. Also the burden upon the friction rod is greatly reduced so that 10 less power is required and smoother operation secured.

In addition, the invention permits of the knitting of a "triple heel" or "heel within a heel" by means of five carriers instead of the usual minimum of seven, thus freeing two carriers for other uses. In spite of the continual demand for more and more carriers manufacturers of flat knitting machines have been unable to equip their machines with more than eight and, generally, with 15 not more than seven. This invention which, in effect, increases the number of carriers by two, is of great practical importance, particularly since it can be applied without difficulty to old machines having a more limited number of carriers.

A further feature of the invention is that providing multiple means for driving each rod over full width courses to insure against failure of the driving means to effectively engage with its carrier rod.

One form of the invention and a modification 30 of a part thereof are shown in the drawings, of which

Figure 1 is a plan view of a part of a flat knitting machine equipped with this invention;

Fig. 2 is an end elevation of a part of the carrier rod driving mechanism shown in Fig. 1 viewed from the line 2—2 of Fig. 1 in the direction indicated by the arrows;

Fig. 3 is an end elevation of another part of 40 the carrier rod controlling mechanism viewed from the line 3—3 of Fig. 1 in the direction indicated by the arrows;

Figs. 4 and 5 are diagrammatic views of the 45 position of the carrier rods and driving connections at different stages of the knitting operations;

Fig. 6 is a plan view of a modified form of one 50 of the carrier rod driving mechanisms;

Fig. 7 is an end elevation in section showing 55 one pair only of the levers shown in Fig. 6;

Fig. 8 is a corresponding front elevation viewed from the line 8—8 of Fig. 7 in the direction indicated by the arrows; and

Fig. 9 is a similar and similarly viewed front elevation.

In general the machine may be a standard flat knitting machine for the production of full fashioned hosiery. A part of such a machine is shown diagrammatically in Fig. 1. Only three carrier rods 1, 2 and 3 are shown. The remainder are not required for this description. The usual end stops in the narrowing heads are also diagrammatically indicated at 4 and 5 and the usual friction rod 12 which is reciprocated by the customary Coulter motion. Mounted upon friction rod 12 is a friction box 13 provided with the usual friction devices. Upon friction box 12 are pivotally mounted fingers 14, 15 and 16, the respective lengths of which are such that their ends overlie carrier rods 1, 2 and 3 respectively. All three fingers are mounted on a common shaft 17 in such a way that they may be individually 20 rocked in a vertical plane.

These fingers also extend rearwardly from their pivots as arms 18, 19 and 20 which terminate substantially beneath cross bar 21 of frame 22, which is also mounted upon or is an integral part 25 of friction box 13. The sides 22^a of frame 22 are extended downwardly to form supports for a bearing 23 slidably surrounding a shaft 24 so that frame 22, although it can slide longitudinally, is rigidly braced against other movement insuring that the various parts of the device will be maintained in correct position with respect to the carrier rods. Each of the arms 18, 19 and 20 is connected to cross bar 21 of frame 22 by means of a spring 25. Thus normally the fingers will 30 be maintained in "down" position with their ends slightly above their respective rods. Rocking of fingers 14, 15 and 16 is automatically effected by cams 26, 27 and 28 respectively, mounted on a changing shaft 29 which is rotatably mounted 35 in suitable bearings so that it overlies the rear end of arms 18, 19 and 20. Each of the cams 26, 27 and 28 is slidably mounted upon changing shaft 29, the hub of each being provided with one or more splines 30 which engage with corresponding 40 spline slots 31 in changing shaft 29. Thus although cams 26, 27 and 28 are slideable upon changing shaft 29 any rotation of shaft 29 will impart a corresponding rotation to the cams. Cams 26, 27 and 28 are mounted in proper position 45 with respect to each other and to the arms 18, 19 and 20 by any suitable means and engage with those arms through the medium of a roller 32 on each arm. Thus when friction box 13 is reciprocated by friction rod 12 not only the fingers 14, 50 15 and 16 and arms 18, 19 and 20 but also rollers 32 and cams 26, 27 and 28 will reciprocate as a unit, the cams sliding along shaft 24 and maintaining their operative alignment with the arms. Each of cams 26, 27 and 28 is so shaped and its 55 working surface so distributed about the shaft that the finger which it controls will be maintained in its raised and lowered positions at appropriate times during the knitting operation by suitable rotation of shaft 29.

Shaft 29 may be rotated by any suitable mechanism which will impart proper timing to the cams. The mechanism shown in Fig. 1 for rotating shaft 29 consists of a cam 35 upon the main cam shaft 36 which operates a rock lever 37 through roller 38. Lever 37 in turn rotates shaft 29 in a step by step manner through a pawl 39 and ratchet wheel 40. This form of drive is well known to those skilled in the art and can be 60 designed by them to impart the required speed of

rotation to shaft 29 to harmonize its action with the knitting cycle.

The purpose of fingers 14, 15 and 16 is to translate the reciprocation of friction rod 12 to carrier rods 1, 2 and 3 in accordance with the requirements of the knitting operation being performed. To make this possible carrier rods 1, 2 and 3 are provided with driving blocks 41, 42 and 43 respectively, so positioned on each rod as to be engageable with the corresponding finger 14, 15 or 16 at either end of each stroke and at any intermediate point. In one form of the device each of the driving blocks 41, 42 and 43 is of the form best shown in Fig. 8 and consists of a metallic block attached to and projecting above the carrier rod and provided with sloping surfaces 44 and 45 leading up to a centrally positioned rectangular depression 46 of suitable size to receive the end of a finger.

It will be apparent that whenever during the 20 traverse of the friction rod one of the fingers 14, 15 or 16 is engaged in a corresponding recess 46 of its drive block the carrier rod will also be reciprocated either to the right or left.

It will also be evident that whenever a finger 25 in its "down" position approaches the drive block of its corresponding carrier rod it will ride up one or the other of the sloping surfaces 44 or 45, depending upon the direction of approach and will pick up the carrier rod by snapping into recess 45 30 and that this connection will be maintained until the finger is raised out of the recess by its cam.

As fully described in the Friedmann patent referred to above, the outstanding characteristic of the ringless fabric which the selected form of 35 this invention is primarily designed to produce is that while each course for the greater part of its width is composed of a different thread from that of the adjacent courses the two other threads also appear in the selvages of each course. The 40 mechanism thus far described is employed to lay the different threads in rotation over the full fabric width and also to lay one of the other threads outwardly across a selvage.

To lay the other thread inwardly across the 45 selvage additional mechanism is employed. That shown consists of two frictions 47 and 48 which may be standard in all respects mounted on friction rod 12 and provided with fingers 49 and 50 respectively, the inner sides of which are adapted 50 to engage with drive blocks on each carrier rod such as 51 and 54 on carrier rod 1; 52 and 55 on carrier rod 2; 53 and 56 on carrier rod 3.

Since frictions 13, 47 and 48 are all mounted upon friction rod 12, they can move with the 55 friction rod as long as the carrier rods are free to move, but each of them is also free to stop without affecting the operation of the others whenever a connected carrier rod stops.

For example, assuming the carrier rods to be 60 in the positions shown in Fig. 1 (rods 1 and 3 at the left against end stops 4, and rod 2 so that its thread carrier is over the inner edge of the right selvage); that the next stroke of the friction and carrier rods will be from left to right and that 65 carrier rod 1 will lay the full width thread, then finger 14 will be engaged with drive block 41 on carrier rod 1. When this friction rod stroke to the right occurs finger 14 will propel carrier rod 1 all the way across the fabric until it strikes end 70 stop 5, as shown in Fig. 4, whereupon the carrier rod 1, finger 14 and its friction 13 will stop, the friction rod 12 continuing to the end of its stroke in the usual way.

Also finger 15 of friction 13 will have been low- 75

ered into its "down" position so that during this stroke it can pick up carrier rod 2 by engaging drive block 42 and propel it outwardly across the right selvage. Meanwhile, frictions 47 and 48 have been moving to the right with friction rod 12 and since finger 49 of friction 47 engages drive block 53 on carrier rod 3 it will propel carrier rod 3 inwardly across the left selvage at the inner edge of which the carrier rod and, consequently, friction 47 also will be stopped by a suitable stop.

The result of these operations is depicted in Fig. 4. Rods 1 and 2 have been traversed by the fingers 14 and 15 of friction 13 and rod 3 by finger 49 of friction 47. Friction 48 has not participated but has merely moved toward the right with friction rod 12.

The following stroke is depicted in Fig. 5. Here carrier rod 2 has been driven to the left all the way across the fabric by finger 15 of friction 13 which has remained in engagement with drive block 42. Carrier rod 3 has been picked up by finger 16 at the inner edge of the left selvage and driven outwardly across that selvage, and carrier rod 1 has been driven inwardly across the right selvage by finger 50 of friction 48 through drive block 54.

In this way each rod is driven across the full width of the fabric, then inwardly across a selvage, then outwardly across the same selvage, then across the full width again but in the opposite direction, and so on in successive courses and simultaneously the other rods are driven in a similar manner each one step behind the other. The three fingered friction 13 selects the full course rod and also the rod to be driven by one or the other of frictions 47 and 48. That is to say, the selective mechanism is mechanically associated with friction 13 only but operatively determines the functioning of the other two frictions also by taking control of two carrier rods during each stroke leaving only the third rods to be cared for by the other.

A means for limiting the inward traverse of the carrier rods working upon the selvages is, of course, essential. Any suitable mechanism can be employed for this purpose. The essential requisite is that it shall be able to stop the traverse of any one of the carrier rods at any desired time without interfering with the traverse of the other carrier rods. A suitable automatic mechanism for this purpose is shown in Figs. 1 and 3. Briefly, it consists of two series of stops 57, 58 and 59, 60, 61 and 62 adapted to be moved into and out of engagement with corresponding stops on the carrier rods. As shown, stops 57, 58 and 59 limit the inward movement to the right of carrier rods 1, 2 and 3 respectively, through carrier rod stops 64, 65 and 66. Similarly stops 60, 61 and 62 limit the inward movement to the left of carrier rods 1, 2 and 3 respectively, through carrier rod stops 67, 68 and 69 respectively. Stops 57, 58 and 59, 60, 61 and 62 are moved into and out of engaging position by levers 70 operated by cams 71 on shaft 29 in a manner similar to that in which the driving fingers 14, 15 and 16 are operated by their cams on the same shaft. In Fig. 1 stop 61 is down and has stopped carrier rod 2 at the inner edge of the right selvage through carrier rod stop 68. In Fig. 4 this stop has been lifted and stop 59 lowered so that the travel of carrier rod 3 has been terminated on the inner edge of the left selvage through the engagement of carrier rod stop 66. In Fig. 5 stop 68 is down and has terminated the traverse of

carrier rod 1 at the inner edge of the right selvage through its engagement with carrier rod stop 67.

The longitudinal position of the adjustable stops with respect to the carrier rods is determined by the threaded spindle 72 upon which they are mounted so that, through rotation of the spindle by suitable means such as the pawl and ratchet mechanism shown, the width of the selvages can be varied at will and the contours of the inner edges of the selvages given any desired configuration without regard to the character of the outer edges.

Another form of adjustable stop mechanism suitable for the purposes described is disclosed in Patent No. 2,030,697 granted to Albert Friedmann on February 11, 1936. However, as already stated, any suitable mechanism may be employed.

Of course, it is essential that the driving engagement of the selective driving fingers 14, 15 and 16 with their carrier rods should not fail at any time. When the rods are driven at high speed there is a possibility of such failure since the width of recess 46 of the drive dog is, at most, only slightly greater than the width of the finger so that spring 25 may not act quickly enough to lower the finger before its leading edge has passed beyond the recess. To remove all possibility of this the modified form of selective driving fingers illustrated in Figs. 6 to 9, may be substituted for those hereinbefore described. As shown in Fig. 6 each of fingers 14, 15 and 16 has, in effect, been split longitudinally into two fingers 14^a, 14^b; 15^a, 15^b; 16^a, 16^b, and each provided with a cam roller and spring. The two cam rollers 32^a and 32^b of each pair of fingers are engageable with one of the cams 26, 27 or 28 shown in Fig. 1 so that the two fingers of each pair can be lifted as a unit by the cam. However, when the cam permits them to drop each finger is maintained in down position by its individual spring 25 so that the fingers will act independently one following the other up incline 44 or 45 and into recess 46 of the drive dog. This is illustrated in Figs. 7, 8 and 9 in which it is assumed that fingers 16^a and 16^b have approached drive block 43 on carrier rod 3 from the right. In Fig. 8 finger 16^a has already dropped into recess 46 and is about to be followed by its companion finger 16^b after which they are positioned side by side as shown in Fig. 9. With this construction not only is the width of each finger somewhat less than half the recess 46 so that it has plenty of time to drop into the recess but each finger of the pair is approximately only half as heavy as a single finger so that it can be made to drop faster.

The modified construction has the further merit that if the leading one of the fingers should manage to jump recess 46 it would be extremely unlikely that its companion finger would follow suit so that the carrier rod would still be operatively connected to the friction. Fig. 8 will serve to illustrate this contingency also if it is assumed that the fingers are moving from left to right. Upon this assumption finger 16^a has failed to enter recess 46 but finger 16^b has functioned properly and will drive carrier rod 3 as soon as it has absorbed the space ordinarily occupied by the other finger. If this pair of fingers are to function upon the following stroke also, finger 16^b will drop into its proper place in recess 46 as soon as finger 16^a has made room for it by its initial movement across the recess.

While the description herein has been confined

to a mechanism for driving three carrier rods only in a specific manner it will be understood that the invention may be utilized for driving a greater number of rods by providing the required number of selective driving fingers and auxiliary apparatus and the required number of plain frictions for the rods not controlled by the selective friction.

It will also be realized that the modified form 10 of the selective driving unit alone can be utilized for driving a plurality of carrier rods in rotation by merely modifying the arrangement of the operating cams to meet the requirements.

What I claim is:

15. 1. In a flat knitting machine provided with a reciprocable friction rod and more than two carrier rods; carrier rod control mechanism comprising a friction device on said friction rod for selecting and driving any two of said carrier rods during any traverse of the friction rod and other friction means on said friction rod for driving another of said carrier rods in the same direction during the same traverse of the friction rod.
20. 2. In a flat knitting machine provided with a reciprocable friction rod and carrier rods; carrier rod control mechanism comprising a friction device upon said friction rod engageable with any of the carrier rods to drive them in one direction only, a second friction device upon said friction rod engageable with any of the carrier rods to drive them in the opposite direction only, and a third friction device upon said friction rod engageable with any of said carrier rods to drive them in either direction, said third device also 30 constituting a means for selecting the carrier rods to be driven by the first and second devices.
35. 3. In a flat knitting machine provided with a reciprocable friction rod and carrier rods; carrier rod control mechanism comprising a friction device on said friction rod for driving one carrier rod across the full width of the fabric and for driving another carrier rod outwardly across the selvage during a traverse of the friction rod and another friction device also on said friction rod for driving a third rod inwardly across the other selvage during the same traverse of the friction rod.
40. 4. In a flat knitting machine provided with a reciprocable friction rod and carrier rods; carrier rod control mechanism comprising a friction device on said friction rod provided with a plurality of carrier rod driving means each of which is engageable with a different carrier rod, means for engaging any one of said carrier rod driving means with its respective carrier rod to drive it across the full width of the fabric, means for engaging any of said carrier rod driving means with its carrier rod to drive it outwardly across a selvage and another friction device on said friction rod adapted to engage and drive inwardly across the other selvage a carrier rod not driven by said other driving means.

5. In a flat knitting machine provided with a reciprocable friction rod and carrier rods; carrier rod control mechanism comprising a friction device on said friction rod provided with a plurality of carrier rod driving means each of which is engageable with a different carrier rod, means movable with said friction device for engaging any one of said carrier rod driving means with its respective carrier rod to drive it across the full width of the fabric, means for engaging any 10 of said carrier rod driving means with its carrier rod to drive it outwardly across a selvage and another friction device on said friction rod adapted to engage and drive inwardly across the other selvage a carrier rod not driven by said 15 other driving means.

6. In a flat knitting machine provided with a reciprocable friction rod and carrier rods; carrier rod control mechanism comprising a friction device on said friction rod provided with a plurality of carrier rod driving means each of which is engageable with a different carrier rod, means for engaging any one of said carrier rod driving means with its respective carrier rod to drive it across the full width of the fabric, means for 20 engaging any of said carrier rod driving means with its carrier rod to drive it outwardly across a selvage and another friction device on said friction rod adapted to engage and drive inwardly across the other selvage a carrier rod not driven by said 25 other driving means.

7. In a flat knitting machine provided with a reciprocable friction rod and carrier rods; carrier rod control mechanism comprising a friction device on said friction rod provided with a plurality of means for engaging and driving each carrier rod in either direction, said plurality of means comprising a pair of fingers engageable individually or collectively with its carrier rod.

8. In a flat knitting machine provided with a reciprocable friction rod and carrier rods; carrier rod control mechanism comprising a friction device on said friction rod provided with a plurality of means for engaging and driving each carrier rod in either direction, said plurality of means comprising a pair of fingers automatically engageable individually or collectively with its carrier rod.

9. In a flat knitting machine provided with a reciprocable friction rod and carrier rods; carrier rod control mechanism comprising a friction device on said friction rod provided with a plurality of means for engaging and driving each carrier rod in either direction, said plurality of means comprising a pair of fingers automatically engageable individually or collectively with its carrier rod, and means for disengaging either one or both of said fingers from its carrier rod.

ARNOLD FRIEDRICH VERBEEK.
